LOOM FOR WEAVING TUFTED PILE FABRICS

Isaac Bradley Bassindale, Grasscroft, near Oldham, and Fred Brown Schofield, Longsight, Royton, near Oldham, England, assignors to Platt Brothers and Company Limited, Oldham, England

Application March 16, 1950, Serial No. 159,532
In Great Britain March 17, 1949

3 Claims. (Cl. 139—336)

1

This invention of improvements relating to the looms for weaving tufted pile fabrics refers to spool Axminster carpet looms and in particular to the mechanism for disengaging and removing tube frames carrying spools of tuft yarn from the carrying chains and conveying them to the place where the tube frames are caused to insert the tuft yarn between warp threads and afterwards restoring the tube frames to the carrying chains.

The said mechanism includes clasping means for engagement with the tube frames mounted by means of pivots in transferring arms carried and movable by a shaft mounted to be oscillated by means of a cam in to a top position for the clasping means to receive a tube frame from the carrying chains then in to a bottom position for tuft yarns to be inserted between the warp threads and subsequently to a top position to restore the tube frame to the carrying chains.

There is a transferring arm at each side of the loom and also there may be a transferring arm or transferring arms intermediate of said outer transferring arms.

If for any reason a tube frame end bracket is not in correct position for the respective clasping means on the transferring arm to properly engage the tube frame the upward movement of the transferring arm would cause the clasping means to strike the said end bracket with some force and the resultant shock being transmitted to the transferring arm frequently causes breakage of said arm.

The present invention obviates this disadvantage by forming each transferring arm in two portions hingedly connected together and normally held in operative position by a shear pin passing through the joint on the side of the pivot adjacent to the clasping means and spaced at a suitable distance from the pivot pin of the joint.

If the clasping means meets any obstruction the resultant shock shears the aforesaid pin and the forward portion of the transferring arm drops about the said pivot and carries the clasping mechanism out of the way of the tube frame end bracket.

In order to stop the loom should the transferring arm be broken in the manner described by shearing of the pin two terminal contact points are provided one an insulated bridge contact on the forward portion of the transferring arm and a second provided by the rear portion of the transferring arm. The contacts are so disposed that when the aforesaid pin is sheared and the forward portion of the transferring arm drops

2

the two contacts meet and thereby complete a low voltage electric circuit whereby to energise a relay which in turn operates the starter to break the electric circuit to the driving motor and bring about stoppage of said motor whereupon the loom is brought to a standstill.

To restore the transferring arm to operative condition it is only necessary to raise the fallen forward portion into alignment with the rear portion and to insert a fresh shear pin.

Description will now be given of a practical embodiment of the invention reference being made to the accompanying drawings in which the same reference characters indicate corresponding parts in the several figures of the drawing.

In the drawings Fig. 1 is a side view of a transferring arm constructed according to the invention, shown in normal position; Fig. 2 is a side view of Fig. 1 looking in the direction of the arrow "A"; Fig. 3 is a fragmentary plan view of Fig. 1 looking in the direction of the arrow "B"; Fig. 4 is a diagram of the electric circuit of the stop motion.

For convenience in the following description reference will only be made to one transferring arm, but it is to be understood that there are similar transferring arms intermediate of and/or at the opposite side of the loom.

Referring to Figs. 1 to 3 of the drawings the transferring arm is formed in two portions, that is a rear portion 10 formed with a bifurcated end 10^a and a forward portion 11 having a tongue 11^a at one end for engagement in the bifurcated end 10^a of the rear portion 10, and being adapted for carrying at its extremity 11^b clasping means, not shown. The two portions 10 and 11 are hingedly connected together by a bolt 12 passing through holes in the arms of the bifurcated end 10^a and the tongue 11^a and held therein by a nut 12^a, the bolt 12 providing a pivot for the forward portion 11 of the transferring arm. The two portions 10, 11 of the transferring arm are normally held in operative position by a shear pin 13 passing through the joint on that side of the pivot bolt 12 adjacent to said clasping means.

Secured to the forward portion 11 between insulation blocks 14, 15 is a contact bridge plate 16 with a terminal screw 17 and forming one contact terminal in a low voltage electric circuit, the other terminal of which is formed by the transferring arm.

When the transferring arm encounters an obstruction, the shear pin 13 is broken and the forward portion 11 of the transferring arm, pivots

downwardly to clear the obstruction thus bringing the insulated bridge terminal 16 carried by said portion 11, into contact with the adjacent end of the rearward portion 10 of the transferring arm so completing the low voltage electrical circuit to effect loom stoppage.

The downward movement of the forward portion 11 is arrested when the contact is made.

The sequence of operations of the electric stop motion will be described with reference to the diagram shown in Fig. 4, in which B indicates a transformer for low (safe) voltage; C indicates a trip relay with one normally closed contact indicated at C¹; D indicates a relay with two normally open contacts D¹, D²; E indicates a trip contact on the loom; F indicates a change-over push unit actuated by the loom starting handle, having four terminals F¹, F², F³ and F⁴; G indicates a reset button on the loom; H indicates a signal lamp.

The operation is as follows:

With the loom running normally, all the contacts and relays are as shown in the diagram, the transferring arm being as shown in Fig. 1. When the transferring arm is broken at the joint and contact is made to complete the low voltage circuit as previously described, i. e. making contact at E, thus energising the relay coil D and closing contacts D¹, D², contact D¹ providing an alternative path for electric current through the relay coil D, making the relay coil D self-retaining and now independent of the contact at E. The contact D² being closed provides a circuit through the contacts F¹, F² and relay coil C, thus breaking contact C¹ which causes the circuit to the electro-motor to be opened automatically and brings about stoppage of the loom, at the same time also releasing the change-over push unit F, breaking contact between F¹ and F² and bridging F³ and F⁴.

The relay coil C is now de-energised and C¹ returns to normal closed position. An alternative circuit then flows through contacts F³, F⁴, lamp H and contact D¹, thus indicating the cause of the stoppage.

The driving motor can be switched on if required and the loom "inched" at the operator's will, but, if the starting handle is moved to full "on" position before removal of the causes of stoppage, the stop motion will again act.

Having rectified the cause of the stoppage and reconstituted the transferring arm, the operator can then press the re-set button G, and the loom is again ready for running.

What we claim is:

1. In a tube frame transferring means for spool

Axminster carpet looms including a pair of transferring arms, clasping means attached to the forward ends of said transferring arms and electric stop motion means embodying a low-voltage electric circuit, each transferring arm being formed in two portions, that is a rear portion for connection to the operative parts of the loom bifurcated at its extremity, a forward portion having a tongue at one end for engagement in the bifurcated end of the rear portion, the opposite end of said forward portion being in operative connection with the clasping means, a bolt passing through holes in the arms of the bifurcated end of the rear portion and the tongue of the forward portion, a nut screwing onto said bolt for securing it in position whereby said bolt serves to hingeably connect the two portions together and to provide a pivot for the forward portion, and a shear pin passing through the arms of the said bifurcated end and through said tongue on that side of the pivot adjacent to the said clasping means, whereby if the clasping means meets any obstruction in the operation of the loom the resultant shock shears the shear pin whereupon the forward portion of the transferring arm drops about the pivot and carries the clasping means out of the way of the obstruction.

2. A tube frame transferring means as claimed in claim 1, in which one portion of each transferring arm is furnished with an insulated bridge terminal comprising a metal plate interposed between two pieces of insulating material and a screw and forming one contact terminal in the low-voltage circuit of the electrical stop motion means, the other contact terminal being provided by the other portion of the transferring arm.

3. A tube frame transferring means as claimed in claim 1 in which the electric stop motion means embodying the low-voltage electrical circuit, includes a transformer for low voltage, a trip relay with one normally closed contact, a relay with two normally open contacts, a changeover push unit having four terminals, a re-set button on the loom, and a signal lamp.
